ILLUMINABLE SIGN

George Nelson, Chicago, Ill., assignor to Price
Brothers, Inc., Chicago, Ill., a corporation of
Illinois

Application October 21, 1953, Serial No. 27,267

Term of patent 7 years

(Cl. D1—12)

To all whom it may concern:

Be it known that I, George Nelson, a citizen of the United States of America and resident of Chicago, in the county of Cook and State of Illinois, have invented a new, original, and ornamental Design for an Illuminable Sign, of which the following is a specification, reference being had to the accompanying drawing, forming a part thereof.

Fig. 1 is a top plan view of an illuminable sign embodying my new design.

Fig. 2 is a front view thereof.

Fig. 3 is a view of one of the like ends thereof.

Fig. 4 is a bottom view thereof.

The dominant features of my design are shown in full lines.

I claim:

The ornamental design for an illuminable sign, substantially as shown and described.
